UNITED STATES PATENT OFFICE.

CHARLIE A. HOBBS, OF BLACKHAWK, MISSISSIPPI, ASSIGNOR OF ONE-HALF
TO DAVID H. HOBBS, OF LEXINGTON, MISSISSIPPI.

PLOW-HANDLE.

SPECIFICATION forming part of Letters Patent No. 671,626, dated April 9, 1901.

Application filed December 7, 1900. Serial No. 39,067. (No model.)

To all whom it may concern:

Be it known that I, CHARLIE A. HOBBS, a citizen of the United States, residing at Blackhawk, in the county of Carroll and State of Mississippi, have invented a new and useful Plow-Handle, of which the following is a specification.

This invention relates to plows, and has for its object to provide an improved handle therefor which is longitudinally adjustable, so as to accommodate the same to operators of different heights. It is furthermore designed to have the adjustable parts rigidly connected, so as to prevent looseness thereof occasioned by wear, and also to provide for rendering old plow-handles adjustable as well as to provide entirely new handles.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is a perspective view of a plow provided with the improved adjustable handles. Fig. 2 is a detail longitudinal sectional view taken through the opposite members of a pair of handles constructed in accordance with the present invention. Fig. 3 is a similar view taken through one member of an old handle, showing the manner of applying the adjustable feature thereto. Fig. 4 is a detail transverse sectional view taken on the line 4-4 of Fig. 3. Fig. 5 is a detail perspective view of one of the wear-plates for the adjustable handle-sections.

Like characters of reference designate corresponding parts in all of the figures of the drawings.

In Fig. 1 of the drawings there has been illustrated a plow-beam 1, having the usual standard 2, carrying a plow 3, and the opposite handle members 4, which are connected to the rear end of the beam and the standard

in any suitable or common manner. These parts are shown to more adequately illustrate the application of the present invention, and therefore may have any desired form.

In carrying out the invention there are provided the opposite adjustable handle-sections 5, which are formed of wood or metal and provided at their outer ends with the usual bowed hand-grips 6. These handle-sections and their connections with the fixed sections 60 are duplicates, and therefore a description of one member is deemed sufficient.

When constructing new handles, the fixed or inner sections 4 are made of suitable lengths without hand-grips at their outer ends and are provided with corresponding intermediate longitudinal slots 7 for the reception of the opposite ends of a transverse brace-rod 8. This rod has its opposite ends projected at suitable distances through the slots and also 70 screw-threaded for the reception of the respective pairs of nuts 9 and 10, embracing the respective handle-sections, so as to prevent endwise displacement of the rod. The outer extremities of the handle-sections are 75 provided with corresponding perforations or openings 11 for the reception of the opposite screw-threaded ends of a transverse brace-rod 12, and the latter is provided with the opposite pairs of nuts 13 and 14, as and for the 80 purpose set forth for the former rod.

Each adjustable handle-section is provided with a transverse perforation or opening 15 in its inner end for the reception of the adjacent projecting end of the transverse rod 8, 85 and the adjacent pair of nuts bear against the inner side of the fixed section and the outer side of the adjustable section, so as to connect the two sections, and by manipulating the opposite pairs of nuts the opposite outer handle-sections may be adjusted longitudinally upon the fixed sections by adjusting the rod 8 longitudinally along the corresponding slots 7. The handle-sections are furthermore held together by means of the substantially U- 95 shaped metallic clips 16, each of which has an intermediate perforation for the reception of the rod 8, with its opposite sides or arms embracing the top and bottom edges of the sections, and is clamped against the inner side of 100

the fixed section by means of the inner member of the adjacent pair of nuts, thereby forming a washer therefor.

The intermediate portion of each adjustable section is provided with a longitudinal slot 17 for the reception of the adjacent projecting end of the rod 12, upon which the adjacent sections are clamped by the adjacent pair of nuts in the manner described for the inner end of the adjustable section. A slotted metallic wear-plate 18 is applied to the outer side of the adjustable section so that its slot corresponds to the slot of the section and is provided with pairs of terminal ears 19, projecting in the same direction from the opposite longitudinal edges of the plate and embracing the top and bottom edges of the handle-sections, so as to form additional braces therefor. Suitable fastenings 20 are driven through the ears and into the adjustable section, so that the plates are carried by said adjustable sections and are removable therewith without removing any other fastenings. It will be understood that these plates 25 strengthen the slotted portions of the handle-sections and also take the wear of the outer nuts 14.

From the foregoing description it will be understood that the inner ends of the adjustable sections are provided with fastening devices that are slidably received within the slotted portions of the fixed sections, said fastenings being the ends of the rod 8, while the outer ends of the fixed sections are provided 35 with fastenings—viz., the ends of the rod 12—which are slidably adjustable in the slotted portions of the adjustable handle-sections. By this arrangement the handles may be adjusted longitudinally, and at the same time 40 the sections thereof are rigidly connected and braced, so as to prevent looseness.

In applying the present invention to old plow-handles which are connected by means of one or more transverse braces 21, as indicated in Fig. 3 of the drawings, one handle member only being shown, the bolts 22 and 23 take the place of the rods 8 and 12, respectively, the other parts being exactly the same. Thus the only change required in the 50 old handles is to cut off the grip portions thereof and provide each section with a longitudinal slot 7, as described in the first form of the invention. It will now be understood that the fastenings 22 and 23 correspond to the fastenings formed by the ends of the rods 8 and 12.

What is claimed is—

1. The combination with inner fixed plow-

handle sections, having corresponding longitudinal slots, and laterally-projecting fastening devices, of opposite outer adjustable 60 handle-sections, which have corresponding longitudinal slots for the adjustable reception of the respective fastenings of the fixed sections; and also laterally-projecting fastenings adjustably received within the respective slots of the fixed sections.

2. The combination with an inner fixed plow-handle section, having a laterally-projecting fastening device, of an outer longitudinally-adjustable handle-section, having a 70 longitudinal slot adjustably receiving the fastening, and a wear-plate secured to the outer side of the adjustable section, and having a slot corresponding to the slot in the fixed handle-section, and pairs of laterally-projecting 75 ears embracing the opposite sides of the two handle-sections.

3. The combination with longitudinally-adjustable plow-handle sections, having a slot-and-bolt adjustable connection, of a substantially U-shaped metallic clip which is independent of the handle-sections, embraces the overlapped portions of the handle-sections, and is provided with an intermediate perforation receiving the bolt, the intermediate 85 portion of the clip being held between one of the handle-sections and the adjacent head of the bolt, whereby the clip is carried by and is adjustable with the bolt.

4. The combination with opposite inner 90 fixed plow-handle sections having corresponding intermediate longitudinal slots, and a transverse brace-rod connecting the outer ends of the sections and projecting at the outer sides thereof, of opposite outer longitudinally-adjustable handle-sections, having outer terminal hand-grips, intermediate corresponding longitudinal slots adjustably receiving the respective projecting ends of the brace-rod, a transverse brace-rod connecting 100 the inner ends of the adjustable sections, passing adjustably through the corresponding slots of the fixed sections and projecting beyond the adjustable sections, and pairs of nuts fitted to the ends of both rods and adjustably embracing the respective handle-sections.

In testimony that I claim the foregoing as my own I have hereto affixed my signature in the presence of two witnesses.

CHARLIE A. HOBBS.
